UNITED STATES PATENT OFFICE.

HANS BAARTH, OF DRESDEN, GERMANY.

REVERSE-PLATING DEVICE FOR CIRCULAR-KNITTING MACHINES.

Application filed April 8, 1927, Serial No. 182,121, and in Germany April 10, 1926.

This invention relates to a device for producing reverse-plating effects in circular knitting machines, and consists in the provision of reversing sinkers having serrated edges wherewith to support the yarns, means being provided for imparting retrograde movement to said sinkers so as to reverse the relative position of the yarns in the needle head before the loops are formed.

10 The means for retracting the reversing sinkers preferably consist of adjustable guide segments which are controlled by spring-pressed slides and by bell-crank which actuate said slides and which are rocked by the 15 patterning cams.

In order to produce reverse-plating in one part of the work while normal plating is carried out in another part, reversing sinkers are used having butts of different heights which 20 are operated independently by segments arranged on different levels, the higher butts being notched to admit the lower segment without being affected thereby.

Fig. 1 of the accompanying drawings represents a part section of the head of the machine,

Fig. 2, a plan view of the same,

Fig. 3, a diagrammatic side view illustrating the laying of the threads,

30 Fig. 4, the corresponding plan view,

Fig. 5, a sectional view of the sinker-guides,

Fig. 6, a view of the sinkers for the ground work of the fabric.

35 Figs. 6^a and 6^b, views of the butts of the reversing sinkers,

Fig. 7, a view showing the initial position of the threads on the sinkers,

40 Figs. 7^a and 7^b, views showing different stages in the reversing process, and

Fig. 7^c, a view showing the threads reversed.

For ordinary plated work, the ground thread G and the plating thread P are laid in the needles as shown in Figs. 3 and 4. The 45 threads are fed to the needles from different angles and placed side by side on the sinker edge as shown in Fig. 7, the plating thread being outermost so as to appear on the outside of the loop and on the face of the fabric.

50 For producing any desired stripes as well as chequered and figured patterning, the position of the threads is reversed in a needle head wherever required while the needles travel through the distance A—B in Fig. 3. This 55 causes the plating thread to be worked as ground thread and vice versa, and the knit-

ting will proceed as usual without leaving any loose threads at the back of the fabric.

The reversal is effected by the provision of reversing sinkers having, instead of the plain 60 edge 16 (Fig. 6) a serrated edge 18 (Figs. 7 to 7^c). The guides for these sinkers are adjusted by the patterning mechanism so as to cause the sinkers to be retracted from their normal path while the needles travel from A 65 to B (Fig. 3). By this movement of the reversing sinkers, the ground thread G is pressed over the plating thread P by the sinker projections, as shown in Figs. 7^a and 7^b, and drops into a notch at the opposite side 70 of the same, as shown in Fig. 7^c, so as to appear outermost in the loop and on the face of the fabric.

The retracting movement of the reversing sinkers is effected by the backs 1 of guide segments 3 and 4 which are controlled by slides moving between guide plates 5. The segments are shifted into and out of operative position by springs 10 and by bell-crank 8 and 9 which latter engage lugs 6 on the 80 slides. The cam shaft which operates the thread guides and which is rotated by means of a ratchet wheel and a pawl 14, is provided with cams 11 and 12 for rocking the bell-crank. The crests 13 of the cams move the 85 sinker guides into operative position and determine the number of courses during which reversal of threads is to take place.

In the arrangement described there are three kinds of sinkers 22, 23 and 24, shown 95 respectively in Figs. 6, 6^a and 6^b. The sinkers 22 are ordinary sinkers and are employed wherever no reverse-plating is required. The sinkers 23 and 24 are reversing sinkers and are applied to different positions of the needle 100 cylinder in order to allow normally plated fabric to be produced in one part of the work, for instance in the sole or in the heel of a stocking, while patterned reverse-plating is carried out in another part, for instance in 105 the top of the foot.

The guide segments 3 and 4 are superimposed on a guide segment 21 which latter operates all the sinkers in the usual manner for sinking the loops. The reversing sinkers are recessed so as to allow of being retracted by the segments 3, 4 without being obstructed by the segment 21. The butts of the sinkers 22 are below the level of the segments 3 and 4 and will therefore remain unaffected by the retrograde movements of the latter, and the butts of the sinkers 23 are be-

low the level of the segment 4 so as to allow the sinkers 24 to be operated independently of the sinkers 23. To allow the sinkers 23 to be operated independently of the sinkers 24, 5 the butts of the latter are formed with notches 26 into which the segment 3 is admitted.

I claim:

1. In a circular knitting machine, a reverse-plating device comprising reversing sinkers having serrated shoulders wherewith 10 to support the yarn, and means for imparting to said sinkers a movement in opposite direction to the sinking movement so as to reverse the relative positions of the yarns in 15 the needle head before the loop is formed.
2. A structure as claimed in claim 1 where- 20 in the operating means for the reversing sinkers comprise adjustable guide segments ar- 25

ranged one above another, spring-pressed slides controlling said segments, bell-cranks 20 for actuating the slides, and patterning cams for operating the bell-cranks.

3. In a circular knitting machine, a reverse-plating device comprising reversing sinkers having serrated shoulders whereton to 25 support the yarns and butts of different heights for employment in different parts of the work, guide segments for said sinkers arranged at different levels for co-operation with different butts, the higher butts having 30 notches wherein the lower segment can work without affecting said higher butts, spring-pressed slides controlling said segments, bell-cranks for actuating the slides, and patterning cams for operating the bell-cranks.

HANS BARTH.
